US0D1018206S

(12) **United States Design Patent** (10) **Patent No.:** **US D1,018,206 S**
(45) **Date of Patent:** **** Mar. 19, 2024**

(54) **CONTAINER**

(71) Applicant: **Runway Blue, LLC**, Alpine, UT (US)

(72) Inventors: **John R. Omdahl, II**, Lindon, UT (US);
David O. Meyers, Layton, UT (US)

(73) Assignee: **Runway Blue, LLC**, Alpine, UT (US)

(**) Term: **15 Years**

(21) Appl. No.: **29/830,658**

(22) Filed: **Mar. 14, 2022**

(51) LOC (14) Cl. **07-01**

(52) U.S. Cl.

USPC **D7/536; D7/510**

(58) **Field of Classification Search**

USPC D7/300.1, 394, 395, 507, 509, 510, 511,
D7/523, 531, 532, 533, 534, 536, 608;

D9/435; D24/197; 220/592.16, 592.17

CPC A47G 19/22; A47G 19/2205; A47G
19/2211; A47G 19/2266; A47G 19/2288;
A47J 43/27; A47J 41/02; B65D 47/066

(57) **CLAIM**

The ornamental design for a container, as shown and described.

DESCRIPTION

FIG. 1 is a top rear isometric view of a container showing the claimed design;

FIG. 2 is a top front isometric view thereof;

FIG. 3 is a bottom rear isometric view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is a top rear isometric view thereof including a straw.

The broken lines in the figures show portions of the container or environment that form no part of the claimed design.

1 Claim, 9 Drawing Sheets
